Primary Examiner — Jack Reickel*Assistant Examiner* — Michael A Kervin(74) *Attorney, Agent, or Firm* — Lombard & Gelieber LLP; Eric J. Huang(57) **CLAIM**

The ornamental design for a pad for the jaws of a clamp, as shown and described.

DESCRIPTION

FIG. 1 is a front, top side perspective view of a pad for the jaws of a clamp showing my new design;

FIG. 2 is a front, bottom side perspective view thereof;

FIG. 3 is a rear, top side perspective view thereof;

FIG. 4 is a rear elevation view thereof;

FIG. 5 is a front elevation view thereof;

FIG. 6 is a right side elevation view thereof, with the left side elevation view being a mirror image;

FIG. 7 is a top plan view thereof; and,

FIG. 8 is a bottom plan view thereof.

Broken lines are included in the figure drawings to show portions of the article not claimed and form no part of the claimed design.

1 Claim, 8 Drawing Sheets(56)
